(57) **CLAIM**

The ornamental design for a water bottle pouch as shown and described herein.

DESCRIPTION

FIG. 1 is a top, left and front perspective view of a water bottle pouch embodying my new design;

FIG. 2 is a front elevational view thereof;

FIG. 3 is a rear elevational view thereof;

FIG. 4 is a right elevational view thereof, the left elevational view being a mirror image thereof;

FIG. 5 is a top plan view thereof; and,

FIG. 6 is a bottom plan view thereof.

The broken lines in FIG. 1, FIG. 2, FIG. 4, and FIG. 5 illustrate portions of the water bottle pouch that form no part of the claimed design.
